CONVERSION OF ALIPHATIC HYDROCARBONS TO CYCLIC HYDROCARBONS

Justus Friederich Clausen, Amsterdam, Netherlands, assignor to Shell Development Company, San Francisco, Calif., a corporation of Delaware

No Drawing. Application November 26, 1938,
Serial No. 242,568. In the Netherlands December 17, 1937

9 Claims. (Cl. 260—666)

This invention relates to the treatment of hydrocarbons, and it more particularly relates to the production of cyclic hydrocarbons by the treatment of saturated and/or unsaturated aliphatic hydrocarbons or mixtures comprising one or a plurality of such aliphatic hydrocarbons.

An object of the invention is to provide a practical and economical process for the catalytic treatment of hydrocarbon mixtures, such as mineral oil compositions, containing one or more saturated and/or unsaturated aliphatic hydrocarbons whereby at least a part of the aliphatic hydrocarbon content of the treated mixture is converted to naphthenic and/or aromatic type hydrocarbons to result in a more valuable product of higher cyclic hydrocarbon content.

Another object of the invention is to provide a practical and economical process for the conversion of normal or only moderately branched chain aliphatic hydrocarbons of paraffinic or olefinic character, which preferably contain at least six carbon atoms in the aliphatic chain, to aromatic hydrocarbons and/or naphthenic hydrocarbons.

The process of the invention comprises contacting the individual hydrocarbons of aliphatic character or a mixture comprising one or more of such hydrocarbons at an elevated temperature, preferably in the range of from about 400° C. to 600° C., with a solid catalyst mass consisting of or essentially comprising a heavy metal salt of molybdcic acid or tungstic acid.

I have found that the heavy metal salts of molybdcic and tungstic acids, and mixtures essentially comprising one or a plurality of such heavy metal salts, are particularly suitable agents for effecting the conversion of hydrocarbons of aliphatic character to cyclic hydrocarbons, and can be used, with the attainment of commercially practicable yields of cyclic hydrocarbons at temperatures below those at which excessive cracking of the treated and resultant hydrocarbon material occurs. Moreover, it has been found that catalysts consisting of or comprising a heavy metal salt of molybdcic or tungstic acid, particularly when the process is effected in the initial presence of added hydrogen under a moderately elevated pressure, retain their activity over relatively long periods of continuous use and can, when they have finally suffered loss of activity to the extent that their use is no longer practicable, be reactivated and their initial activity substantially restored easily and inexpensively.

While broadly applicable to the conversion of hydrocarbons of aliphatic character to cyclic hydrocarbons, the invention is of particular value and usefulness as applied to the conversion to cyclic hydrocarbons of the aliphatic hydrocarbons of paraffinic or olefinic character which are of straight or only slightly branched structure and possess at least six carbon atoms in the aliphatic chain. Individual aliphatic hydrocarbons of this preferred subgroup are, among others, normal hexane, the normal hexylenes, 2-methyl pentane, the 2-methyl pentylenes, normal heptane, the normal heptylenes, 2-methyl heptane, the 2-methyl heptylenes, 3-methyl heptane, the 3-methyl heptylenes, the normal and only slightly branched octanes, the normal and only slightly branched octylenes, the normal and only slightly branched nonanes and nonylenes and the like. The paraffinic or olefinic normal or only slightly branched carbon skeleton hydrocarbons may be advantageously treated individually, in admixture with each other, or in admixture with one or more other hydrocarbons not of the particular preferred group such as the butanes, the butylenes, the pentanes, the amylanes, the naphthenes, the cyclic olefines, and the like.

The process of the invention may be advantageously applied to the treatment of hydrocarbon mixtures such as the natural and synthetic gasolines, for example, the straight-run gasolines, hydrogenation gasolines, gasolines obtained by cracking, gasolines obtained by polymerization of olefines, followed by hydrogenation of the polymers, gasolines obtained by the reaction of carbon monoxide and hydrogen, and the like. Such hydrocarbon fuel mixtures, after treatment in accordance with the process of the invention whereby at least a part of their content of hydrocarbons of aliphatic character is converted to cyclic hydrocarbons, have considerably higher octane numbers than the treated mixtures and are superior for motor fuel purposes. The resultant mixtures are also useful materials for blending with gasolines having lower octane numbers to improve said gasolines by raising their octane number.

The catalyst used in the execution of the invention consists of or comprises a heavy metal salt of an acid of the group consisting of tungstic acid and molybdcic acid. Suitable catalysts are, for example, the tungstates and molybdates of the heavy metals such as nickel, iron, cobalt, chromium, copper, manganese, vanadium, titanium, zirconium and the like.

The catalysts or catalyst compositions used in the execution of the process may be prepared in a variety of suitable manners known to the art. They may be used, alone or in admixture with one or more catalytic or contact materials, in any suitable solid form as powder, granules, pellets, pellules, etc., or they may together with other catalytic materials be supported on some suitable inactive or active carrying or supporting material such as charcoal, pumice, kieselguhr, fuller's earth, silica gel, alumina, and the like. In some cases, it may be desirable to add to the catalyst a small quantity of a substance capable of acting as a promoter.

15 The desired quantity of the catalyst, preferably in the form of pellules or granules, or supported on granules of a suitable carrier, is employed in manners customary in catalytic processes of this type. The catalyst may be packed 20 into a reaction tube or chamber made of any suitable material and of the desired capacity and heated to and maintained at the desired temperature while the hydrocarbon material to be treated is passed into contact with it, preferably 25 in the vapor phase, at the desired space velocity and under the desired pressure of operation.

The invention is preferably executed at a temperature in the range of from about 400° C. to 30 600° C., although higher or lower temperatures may in some cases be used advantageously. At temperatures below about 400° C., the catalyst is usually not sufficiently active to yield practical conversions. At temperatures greater than about 600° C., it may be difficult to obtain practicable conversions while avoiding excessive cracking and unduly rapid loss of activity of the catalyst. In general, the most favorable temperature in the preferred range of from 400° C. to 35 600° C., is dependent upon the particular hydrocarbon or hydrocarbon mixture treated, upon the particular catalyst or catalyst composition used, upon the contact time to be employed, and upon the desired pressure of operation.

40 The process of the invention may be executed at atmospheric, subatmospheric or superatmospheric pressure. It is preferably effected under moderately superatmospheric pressures of initially added hydrogen. Such hydrogen pressures aid in maintaining the activity of the catalysts over relatively long periods of time while having 45 substantially no deleterious effects on the extent of conversion to cyclic hydrocarbons of the treated material. The advantageous effects of the added hydrogen are best realized by operating under pressures of at least 10 atmospheres, a suitable pressure in some cases being about 50 atmospheres, and a suitable pressure range being from about 10 to about 100 atmospheres.

50 When the individual aliphatic hydrocarbons are cyclized, the reaction may or may not be effected in the presence of added hydrogen or in the presence of some diluent material. Suitable diluents, among which is nitrogen, are materials which have substantially no detrimental effect on the desired reaction and the catalyst under the conditions of execution of the process.

55 The optimum contact time to be employed will depend upon several factors such as the temperature of operation, the pressure of operation, the 60 nature of the hydrocarbon or hydrocarbon mixture treated, the particular catalyst or catalyst composition used, the desired conversion per pass, etc. In general, when operating at temperatures of from 400° C. to 600° C. under hydrogen pressures of from about 10 to 100 atmospheres, good 65

results are obtainable by employing contact times in the practical operating range of from about 10 to about 60 seconds. Shorter or longer contact times may be employed when necessary or desirable.

70 After the catalyst has, due to its use in the execution of the process, suffered loss of activity to the extent that its continued use is no longer practicable, it may be reactivated and its original activity partially or substantially completely 10 restored by discontinuing the operation and passing air or some other suitable oxygen-containing or oxidizing gas into contact with the heated catalytic material. The reactivation may be effected in the presence of an added active or diluent gaseous material such as steam, carbon dioxide, nitrogen, etc. During the reactivation, the catalyst mass may be maintained at a temperature in the range of from about 300° C. to 15 about 800° C. After a reactivation treatment 20 with air, it may, in some cases, be desirable to treat the heated reactivated catalyst with hydrogen prior to its reuse in the process.

25 The following examples are presented for the purpose of illustrating the invention as applied to the treatment of representative aliphatic hydrocarbon mixtures to increase their value as motor fuels by converting a material part of their aliphatic hydrocarbon content to cyclic hydrocarbons. It is to be understood that the invention 30 is not to be regarded as limited to the conditions of operation, the mode of operation, the particular catalysts or the treated materials described in the examples.

Example I

35 The hydrocarbon mixture treated was an octylene fraction which was fractionated from the product resulting from the vapor phase cracking of a solid paraffin wax. The octylene fraction boiled in the temperature range of about 113° C. to 137° C., had an octane number (C. F. R. motor method) of 51, and an octylene content (consisting principally of straight and only slightly branched chain octylenes) of about 85%.

40 The catalyst used was chromium tungstate, which material, in the form of particles of more or less uniform size, was packed into a reaction tube and heated to and maintained at a temperature of about 515° C. while the gaseous octylene fraction, together with hydrogen, was passed into contact with it at such a rate that the average contact time was about 24 seconds, the pressure in the reaction tube being about 10 atmospheres.

45 The effluent reaction mixture was condensed and analyzed. A reaction product having an octane value of 70 was obtained in a yield of about 72% by weight; it contained about 15% by weight of aromatic hydrocarbons and about 30% by weight of naphthenes, the remainder consisting of a mixture of paraffin and olefine hydrocarbons.

Example II

55 The hydrocarbon material treated was an octylene fraction similar to that described in Example I and consisting for the most part of straight or only slightly branched chain aliphatic hydrocarbons.

60 The catalyst was nickel tungstate, and it was used in a manner similar to that described in Example I. The catalyst was maintained at a temperature of about 540° C. while the octylene fraction, together with sufficient hydrogen to make the operating pressure about 50 atmospheres, was passed into contact with it at such 65 70 75

a rate that the average contact time was about 40 seconds.

The liquid reaction product obtained was found to contain about 29% by weight of aromatic hydrocarbons and about 31% by weight of naphthenic hydrocarbons, the remainder consisting of 5 paraffins and olefines.

Results similar to those described may be obtained by the use of other catalysts of the class 10 consisting of the heavy metal salts of molybdic and tungstic acid, other representative members of the class being chromium molybdate, nickel molybdate, iron tungstate, iron molybdate, cobalt tungstate, cobalt molybdate, copper molybdate, 15 etc. Analogous results are likewise obtainable by treatment of other aliphatic hydrocarbon mixtures as well as the individual aliphatic hydrocarbons.

While I have described my invention in a detailed manner and illustrated suitable modes of executing the same, it is to be understood that modifications may be made and that no limitations other than those imposed by the scope of the 20 appended claims are intended.

25 I claim as my invention:

1. A process for the conversion of an octylene to a cyclic hydrocarbon which comprises contacting an octylene with a preformed nickel tungstate catalyst at a temperature of from 400° C. to 30 600° C., said temperature being below that at which excessive cracking occurs.

2. A process for the conversion of an octylene to a cyclic hydrocarbon which comprises contacting an octylene with a preformed chromium tungstate catalyst at a temperature of from 400° C. to 35 600° C., said temperature being below that at which excessive cracking occurs.

3. A process for increasing the cyclic hydrocarbon content of a hydrocarbon mixture boiling essentially within the gasoline boiling 40 range and containing a substantial amount of aliphatic hydrocarbons of at least six carbon atoms which comprises contacting the hydrocarbon mixture with a preformed heavy metal salt of an acid of the class consisting of 45 the molybdic and tungstic acids at a temperature in the range of from 400° C. to 600° C., said temperature being below that at which excessive cracking occurs.

50 4. A process for the production of cyclic hydrocarbons which comprises contacting a hydrocarbon mixture boiling essentially within the gasoline boiling range and containing in substantial amount at least one hydrocarbon of aliphatic 55 character which contains at least six carbon atoms to the molecule with a preformed heavy metal salt of an acid of the class consisting of molybdic and tungstic acids at a temperature in the range of from 400° C. to 600° C. and in the 60 initial presence of added hydrogen under a pres-

sure of at least 10 atmospheres, said temperature and partial pressure of hydrogen being below those at which excessive cracking occurs.

5. A process for the production of cyclic hydrocarbons which comprises contacting the vapors of an aliphatic hydrocarbon boiling essentially within the gasoline boiling range and containing at least six carbon atoms to the molecule with a preformed heavy metal salt of an acid of the class consisting of 10 molybdic and tungstic acids at a temperature of 400° C. to 600° C., said temperature being below that at which excessive cracking occurs.

6. A process for the production of cyclic hydrocarbons which comprises contacting the vapors 15 of an aliphatic hydrocarbon boiling essentially within the gasoline boiling range and containing at least six carbon atoms with a preformed heavy metal salt of an acid of the class consisting of 20 molybdic and tungstic acids at a temperature of 400° C. to 600° C. under a hydrogen pressure of from about 10 to about 100 atmospheres, said 25 temperature and partial pressure of hydrogen being below those at which excessive cracking occurs.

7. A process for the production of cyclic hydrocarbons which comprises contacting an aliphatic hydrocarbon boiling essentially within the gasoline boiling range and containing at least six carbon atoms, together with added hydrogen, 30 with a catalyst essentially comprising a preformed heavy metal salt of an acid of the class consisting of molybdic and tungstic acids at a temperature of 35 from 400° C. to 600° C. and under a superatmospheric pressure, said temperature and partial pressure of hydrogen being below those at which excessive cracking occurs.

8. A process for the production of cyclic hydrocarbons which comprises contacting an aliphatic hydrocarbon boiling essentially within the 40 gasoline boiling range and containing at least six carbon atoms with a catalyst essentially comprising a preformed heavy metal salt of an acid of the class consisting of molybdic and tungstic acids 45 at a temperature of from about 400° C. to about 600° C., said temperature being below that at which excessive cracking occurs.

9. A process for the production of cyclic hydrocarbons which comprises contacting an aliphatic hydrocarbon boiling essentially within the 50 gasoline boiling range and containing at least six carbon atoms with a catalyst essentially comprising a preformed compound of the group consisting of the nickel, iron, cobalt, chromium, copper, manganese, vanadium, titanium and zirconium 55 molybdates and tungstates, at an elevated temperature equal to at least 400° C. but below the temperature at which excessive cracking of the hydrocarbon material occurs.

JUSTUS FRIEDERICH CLAUSEN. 60
